UNITED STATES PATENT OFFICE.

JAMES H. SHAULL, OF CHARLOTTE, MICHIGAN.

DESIGN FOR A TIRE-TOOL.

•6,542.

Specification for Design.

Patented Nov. 2, 1920.

Application filed October 7, 1919. Serial No. 329,140. Term of patent 14 years.

To all whom it may concern:

Be it known that I, JAMES H. SHAULL, a citizen of the United States, residing at Charlotte, in the county of Eaton and State of Michigan, have invented a new, original, and ornamental Design for Tire-Tools, of which the following is a specification, reference being had to the accompanying drawing, forming a part thereof.

The figure illustrates a tire tool in side elevation embodying my new design.

I claim:

The ornamental design for a tire tool substantially as shown.

JAMES H. SHAULL.
